UNITED STATES PATENT OFFICE.

EDGAR W. BREISCH, OF EDGEWOOD, PENNSYLVANIA, ASSIGNOR TO WESTINGHOUSE ELECTRIC & MANUFACTURING COMPANY, A CORPORATION OF PENNSYLVANIA.

TRANSFORMER CONNECTION FOR HOT CATHODE RECTIFIERS.

Application filed November 20, 1920. Serial No. 425,497.

This invention relates to the transformer connections for hot cathode rectifiers, particularly of the type utilizing a single half-wave of an alternating current.

5 In the construction of transformers for supplying rectifiers of the battery-charging type, it is necessary to provide for considerable leakage in the transformer, in order that the direct current voltage will fall off very 10 materially with an increase in current above a predetermined value.

Heretofore, it has been customary to place a small coil for energizing the filament of the rectifier bulb on one leg of the transformer, the transformer being constructed with the load circuit either entirely on that leg or on the other leg. Assume, for example, an auto transformer comprising two coils, one on each leg of a core, said coils being connected in series across a hundred volt line. The normal voltage at each of the coils is then 50 volts.

When a rectifier is connected across one of these coils and a load current is drawn, the 25 voltage will drop to, say, twenty-five volts on that coil, while owing to magnetic leakage around said legs the voltage on the other coil will rise to seventy-five. If, now, the filament coil is placed on the seventy-five volt leg, the filament will receive an abnormal current and tend to burn out.

If, however, the filament coil is placed upon the twenty-five volt leg, the temperature of the filament will not be hot enough, 35 thus approaching the condition of the non-excited filament. Under these conditions, it has been found that the rectified current will continue to flow, even after the filament heating current is entirely interrupted, a small 40 portion of the filament being heated by the rectified current to a temperature high enough to cause this hot portion to continue to give off electrons. As a rule, the filament breaks at the place where this hot spot occurs, after operating under these conditions 45 but a short time. To obviate these difficulties it has been necessary, heretofore, to resort to much larger filaments than would otherwise be necessary.

50 It is the object of my invention, therefore, to provide means for maintaining the filament current constant for all conditions of load, while maintaining the necessary poor regulation of the transformer. This is accomplished by dividing the filament winding,

placing part on one leg and part on the other leg of the transformer, whereby the decrease in the flux of the one leg will be compensated for by the increase in the other leg.

Referring to the drawings, wherein a diagrammatic representation of my invention is shown, I provide an auto-transformer 1 having coils 2 and 3 connected in series across an alternating current supply line, indicated by a plug connector 3a. The midpoint 4 of the auto-transformer is connected to the anode 5 of a bulb 6, said bulb having a filamentary cathode 7 which is adapted to be connected to one terminal of a battery. The other terminal of the battery is connected to the terminal 8 of coil 3. The current for exciting the filament is obtained from two coils 9 and 10, placed on the respective legs of the transformer coil, whereby a constant voltage will be obtained, as hereinbefore explained. It is apparent that taps may be provided in either coil 2 or coil 3 for obtaining different battery voltages and also that different degrees of regulation may be obtained by different numbers of turns of the 80 coils 9 and 10 on the respective legs of the transformer.

The operation of my device is as follows:

The load current is obtained from a transformer winding placed either entirely, or 85 mostly, upon one leg of the transformer coil. The drawing shows the load winding 3 as being placed entirely upon one leg. Under these circumstances, the transformer has very poor regulation. That is, when the 90 load comes on, the flux and hence the voltage in coil 3 drops very materially, while the voltage on coil 2 increases correspondingly. The filament coils 9 and 10 are so proportioned, as to the number of turns in each, 95 that the total electromotive force applied to the filament remains substantially constant.

While I have illustrated my invention in its preferred form, it is to be understood that it is susceptible of various modifications by those skilled in the art and that the claims are to be construed to cover all such modifications except where limited by the state of the art.

I claim as my invention:—

1. The combination with a transformer core having two legs, of coils on each leg, means for supplying power to coils on both legs, means for withdrawing the main part of the load current exclusively from turns 110

on one leg, and means for supplying from said transformer an auxiliary current from turns on both legs.

2. The combination with a transformer core comprising two serially connected magnetizable portions arranged to provide a leakage path therebetween, of coils on each portion, a primary circuit connected across coils on both portions, a secondary circuit connected across turns predominantly on one portion whereby relatively poor voltage regulation is obtained by reason of said leakage path, and an auxiliary circuit including coils on both portions whereby relatively good regulation is obtained.

3. The combination with a rectifying device having a heated filament, of a transformer comprising a core having two legs and a coil on each leg, a supply circuit connected across serially connected turns on both legs, a load circuit including said rectifying device and connected across turns mainly on one leg, and a filament-energizing circuit connected across turns on both legs.

4. The combination with a rectifying device having a heated filament, of a transformer core comprising two serially connected magnetizable portions arranged to provide a leakage path therebetween, a coil on each portion, a supply circuit connected across serially connected turns on both portions, a load circuit including said rectifying device and connected across turns mainly on one portion, whereby relatively poor voltage regulation is obtained by reason of said leakage path, and a filament-energizing circuit so associated with turns on both portions as to obtain relatively good voltage regulation.

5. The combination of an auto-transformer having two legs and coils upon each leg, a load circuit energized mainly by one of the coils upon one leg of said transformer, an auxiliary coil on each leg of said transformer, and a load circuit including said auxiliary coils connected in series.

6. The combination with an auto-transformer comprising a core having two legs and a coil upon each leg, of a main load circuit connected across turns mainly upon a single leg, and an auxiliary load circuit connected across coils upon both legs.

7. In a battery-charging system, the combination with an auto-transformer having two legs and having a coil disposed upon each leg, of a battery circuit including a filamentary bulb, said battery circuit being energized from turns disposed upon a single leg of said transformer, and an auxiliary coil on each leg of said transformer, said auxiliary coils being connected in series with each other to energize the filament of said bulb.

8. A transformer having two legs and a coil on each leg, means for energizing said transformer including turns equally distributed on both legs, means for supplying from said transformer a load current of relatively poor regulation, said load current being drawn from turns mainly on one leg, and means for supplying from said transformer an auxiliary current of good regulation, said last-mentioned means including turns on both of said legs.

In testimony whereof, I have hereunto subscribed my name this 4th day of November, 1920.

EDGAR W. BREISCH.
